UNITED STATES PATENT OFFICE.

GEORGE RANDAULPH SCATES, OF KNOXVILLE, TENNESSEE.

DRY-AIR CLOSET.

SPECIFICATION forming part of Letters Patent No. 645,495, dated March 13, 1900.

Application filed November 27, 1899. Serial No. 738,433. (No model.)

To all whom it may concern:

Be it known that I, GEORGE RANDAULPH SCATES, a citizen of the United States, residing at Knoxville, in the county of Knox and State 5 of Tennessee, have invented a new and useful Dry-Air Closet, of which the following is a specification.

This invention relates to dry-air closets, and has special reference to that class of closets 10 which are especially designed for use in connection with school buildings and other public places wherein it is desirable to preserve the best possible sanitary conditions.

To this end the invention primarily contemplates a novel form of stool provided with means for the separation therein of the solid and liquid matter and the delivery thereof to points beyond the stool, where it may be readily disposed of by a system of ventilation and 20 evaporation, thus preserving the cleanliness of the stool at all times and permitting the escape of odors therefrom. In carrying out this object the invention also contemplates a construction of stool that may be readily set up and separated and which may also be adapted for use in connection with dwellings as 25 well as with public buildings.

A further object of the invention is to provide simple and efficient means for opening 30 up the hopper when occupied.

With these and many other objects in view, which will more readily appear as the nature of the invention is better understood, the same consists in the novel construction, combination, and arrangement of parts herein- 35 after more fully described, illustrated, and claimed.

The essential features constituting the invention are necessarily susceptible to some 40 modification without departing from the spirit or scope thereof; but the preferred embodiment of the improvements is shown in the accompanying drawings, in which—

Figure 1 is a vertical sectional view of a 45 stool embodying the improvements contemplated by the present invention and shown associated with a drying-vault having separate evaporating-flues for the solid and liquid matter. Fig. 2 is a front view of the stool. 50 Fig. 3 is a cross-sectional view on the line 3 3 of Fig. 1. Fig. 4 is a detail plan view of the

tilting drop-door for covering and uncovering the bottom of the hopper. Fig. 5 is a detail elevation of the detachable wall-plate constituting one of the inclosing-walls of the liquid duct or passage at the front of the hopper. Fig. 6 is a general view, partly in elevation and partly in section, showing a series of stools constructed in accordance with the present invention associated with the preferable form of drying-vault.

Like numerals of reference designate corresponding parts in the several figures of the drawings.

In carrying out the invention the improvements contemplated thereby are preferably associated with the type of drying-vault illustrated in the drawings. This vault (designated by the numeral 1) is constructed of masonry and is of a sufficient depth and width 60 to admit of the use of a number of stools therewith, as is customary in setting up closets for use in connection with public buildings, such as school buildings and the like. The vault 1 has built therein a masonry arch 70 2, extending the full length thereof and dividing the interior of the vault into the upper and lower evaporating-flues 3 and 4, respectively. These evaporating-flues 3 and 4 also run the entire length of the vault, and a 80 cement or equivalent flooring 5 is built upon the arch 2 to provide a solid imperforate floor for the upper evaporating-flue 3, which constitutes a receiving-chamber for the solid matter delivered from the several stools, 85 while the lower longitudinal evaporating-flue 4 is also provided with a solid imperforate drainage-floor 6, which receives thereon the liquid matter from the stools and is preferably inclined slightly in a direction toward 90 the vent shaft or stack 7, which arises from the vault to provide for carrying off the products of evaporation from the liquid matter. The separate evaporating-flues 3 and 4 of the

drying-vault open at one end into the vent 95 shaft or stack 7, and at its opposite end the upper of said flues 3 opens directly into the ventilating-chamber 8, in which the draft induces a supply of fresh air which is caused to circulate through the vault, thereby insuring the carrying off of the odors and gases, 100 and thus thoroughly ventilating the entire

apparatus. To provide for insuring this necessary ventilation of the apparatus, a suitable heater 9 is arranged at one end of the vault, and the smoke-pipe 10 of this heater is 5 extended into one end of the lower evaporating-flue 4, so that the smoke and other products of combustion will pass directly into and through the said flue 4, thereby providing for evaporating the liquid matter therein, 10 while at the same time heating up the floor of the upper chamber 3, so as to assist in drying out the solid matter to the combustion-point, this operation being also assisted by the radiated heat from the heater 9, which 15 passes into the adjacent end of the upper evaporating-flue 3.

A series of stools (designated by the letter S) are designed to be arranged in the usual way in connection with the vault, as shown 20 in Fig. 6 of the drawings; but as each of these stools is alike a description of one will suffice for the others. Each stool S essentially consists of an upright hopper 11, adapted to be sustained in upright position with relation to 25 the vault by the base-plate 12. The base-plate 12 covers the top of the vault and serves as a closure for the upper side of the upper evaporating-flue 3, and in connection with the hopper 11 of each stool, the base-plate 30 12 is provided therein with a discharge-opening 13, communicating with the interior of the hopper and with the upper evaporating-flue 3, and surrounding this discharge-opening 13 and conforming to the shape thereof 35 is an integral upstanding seat-flange 14, projected from the upper side of the base-plate and provided at suitably-spaced intervals with integral offset socket portions adapted to receive therein the attaching-feet 15, projected 40 from the bottom peripheral edge of the hopper and secured to the base-plate by means of fastening-bolts 16 or equivalent fasteners. This construction provides a firm seating for the hopper upon the base-plate, 45 while at the same time permitting of the ready removal and replacing thereof.

The upright hopper 11 is preferably of a cast-iron formation and is constructed of two duplicate semi-ovoidal sections 18. These two 50 semi-ovoidal sections 18 of the upright hopper are adapted to register with each other and provide the complete hopper and are provided at their meeting edges with outturned abutting flanges 19, adapted to receive there- 55 through the clamping-bolts 20, which provide for securely fastening the two sections of the hopper together, while permitting of the ready separation thereof whenever required. At its upper edge the said sectional two-part hopper 60 11 is provided with a horizontal top rest-flange 21, upon which is fitted the seat-support 22, having hinged to the rear edge thereof a seat 23 of ordinary form, and as this seat-section cooperates with another part of the apparatus 65 further reference thereto will be hereinafter made.

The upright sectional hopper 11 is of a downwardly-flaring form and is of an approximately ovoidal shape in cross-section, thereby producing a convergent front portion, 70 and within this convergently-arranged front portion is formed a longitudinally-disposed liquid-duct 24. The liquid-duct 24 extends nearly the full length or height of the hopper 11 and is closed in at the front by the contiguous convergent side portions of the hopper, which therefore constitute two walls of the said duct 24, as plainly shown in Fig. 3 of the drawings, and to provide for closing in the remaining or third side of the liquid-duct 80 24 there is employed a separate detachable wall-plate 25. This wall-plate is of an upwardly-flaring width, so that the side edges thereof will follow the curvature of the inner faces of the side sections of the hopper, and 85 by reason of this shape of the wall-plate the same is permitted to register between the front convergent side portions of the hopper and extend across the space between the said portions of the hopper, the said wall-plate being removably retained in position by means of the curved retaining-flanges 26, projected inwardly from the opposite side sections 18 of the hopper and running longitudinally thereof. 95

The detachable wall-plate 25 of the liquid-duct 24 terminates at its upper end a short distance below the upper end of the hopper, so that the duct 24 will receive therein the liquid excrement, it being thus observed that 100 there is a direct separation of the solid and liquid matter within the upper portion of the hopper, and to prevent the upper end of the duct 24 from becoming clogged an approximately triangular guard-screen 27 is fitted 105 therein and is sustained in position by means of suitable supporting-flanges 28. The lower end of the liquid-duct 24 at the bottom of the hopper opens into a drain-port 29, lying above a drain-pipe 30, fitted within the drying-vault, 110 and having its lower end in communication with a discharge-passage 31, which opens into the lower evaporating-flue 4, so as to deflect the liquid products into the same for evaporation by the heat passing through said flue. 115

The bottom discharge-opening 13 for the hopper is adapted to be automatically covered and uncovered by a tilting drop-door 32. This tilting drop-door is of a shape conforming to the shape of the discharge-opening 13, and to insure the free movement of said door the same is provided at one side of its transverse center with an arm portion 33, fitted with a counterbalance-weight 34, to which is also connected an extra weight 35, which normally 125 provides for holding the door closed over the opening 13. The said door 32 is pivotally supported on a hinge-rod 36, journaled in suitable bearings 37, fitted to the under side of the base-plate 12, respectively at opposite 130 sides of the opening 13 therein, and said hinge-rod 36 is provided at one end with a

crank 38, to which is pivotally connected one end of the operating-link 39, the upper end of which is pivoted, as at 40, to the hinged seat-section 23. The weight 35 normally holds the door 32 closed and disposes the crank 38 in such a position as to provide for a slight elevation of the hinged seat-section 23. When this seat-section is occupied, the same is necessarily depressed, thereby causing the drop-door 13 to tilt downward to a position which permits of the solid matter dropping directly from the hopper 11 into the upper evaporating-flue 3, while the liquid matter at the same time enters the liquid-duct 24 and passes into the lower evaporating-flue 4. When the seat-section 23 is relieved, the drop-door automatically returns to its closed position and positively prevents odors arising into and through the hopper.

From the foregoing it is thought that the construction, operation, and many advantages of the herein-described dry-air closet will be readily apparent to those familiar with the art without further description, and it will be understood that various changes in the form, proportion, and minor details of construction may be resorted to without departing from the principle or sacrificing any of the advantages of this invention.

Having thus described the invention, what is claimed as new, and desired to be secured by Letters Patent is—

1. In a dry-air closet, a vault provided with parallel flues arranged longitudinally of the vault and cut off from communication one with the other, combined with a hopper having communication with one of said flues, a normally-open vertical liquid-duct extending through the hopper and in communication only with the other flue, and means for establishing a circulation through the individual and non-communicating flues of the vault, substantially as set forth.

2. In a dry-air closet, the combination of a drying-vault provided with longitudinal flues cut off from communication one with the other, a hopper surmounting the vault and having valved communication with only one of the flues, a vertical liquid-duct extending through and below the hopper and in communication at its lower end with the other of said flues only, the upper end of said liquid-duct being normally open and disposed in close relation to the hopper-seat to effect the initial separation of the liquid from the solid matters, and means for establishing a circulation through the individual and non-communicating flues, substantially as set forth.

3. In a dry-air closet, the combination of a drying-vault provided with the non-communicating flues arranged close together and extending longitudinally of the vault, the series of hoppers surmounting the vault and each having a valved discharge-opening in communication with but one of said flues, a

vertical liquid-duct extending from the upper part of each hopper and in communication at its lower end directly with the other evaporating-flue, and a heater and a stack in communication with opposite ends of the non-communicating evaporating-flues, substantially as set forth.

4. In a dry-air closet, the combination of a vault having separate upper and lower non-communicating flues arranged parallel one to the other and longitudinally of the vault, a vent-shaft in communication with both the flues at one end thereof, a vertical drain-pipe communicating directly with the lower evaporating-flue only, a hopper surmounting the vault and provided with a valved discharge-opening in communication with the upper evaporating-flue only, and a vertical liquid-duct communicating at its lower end with said drain-pipe and having a normally-open upper and screened end disposed contiguous to the hopper-seat, substantially as described.

5. In a closet, the combination of the base-plate provided with an opening therein, and an upstanding rest-flange surrounding said opening and having at intervals offset socket portions, and a hopper surmounting the base-plate and having its lower edge registering within said seat-flange and provided with a plurality of peripheral attaching-feet engaging in said socket portions, and a closure for automatically covering and uncovering said opening in the base-plate, substantially as set forth.

6. In a closet, a hopper comprising the complementary members united together and forming at the front thereof a part of an inclosing wall for a vertical liquid-duct, and a separate wall-plate fitted between said hopper members in opposing relation to the meeting front part thereof and thereby completing the aforesaid liquid-duct, as and for the purposes described.

7. In a closet, a hopper comprising the complementary cross-sectionally-curved members meeting each other at the front and forming, in part, the inclosing wall for a vertical liquid-duct, a separate wall-plate fitted between, and in opposing relation to the meeting front portion of, said members and thereby completing said liquid-duct, and means for detachably holding said wall-plate in position within the hopper, substantially as described.

8. In a closet, a hopper provided with convergent front side portions and having projected from opposite sides thereof longitudinally-arranged retaining-flanges, a detachable wall-plate removably fitted within the hopper against said flanges and having its edges meeting the opposite front side portions of the hopper to close in a liquid-duct extending longitudinally thereof, substantially its full height, substantially as set forth.

9. In a closet, a hopper consisting of sepa-

rate duplicate sections, detachably held together at their meeting edges; a detachable wall-plate removably arranged within the front portion of the hopper to close in a longitudinal liquid-duct, and a guard-screen removably fitted within the upper end of said liquid-duct, substantially as set forth.

In testimony that I claim the foregoing as my own I have hereto affixed my signature in the presence of two witnesses.

GEORGE RANDAULPH SCATES.
